UNITED STATES PATENT OFFICE.

ORIN P. LIVELY, OF PORTSMOUTH, VIRGINIA.

TELESCOPIC MAST.

1,212,968.

Specification of Letters Patent. Patented Jan. 16, 1917.

Application filed February 28, 1916. Serial No. 31,039.

To all whom it may concern:

Be it known that I, ORIN P. LIVELY, a citizen of the United States, residing at Portsmouth, in the county of Norfolk and State of Virginia, have invented certain new and useful Improvements in Telescopic Masts, of which the following is a specification.

Objects of the present invention are to provide a support or column capable of being extended or retracted within maximum and minimum limits; to provide a telescopic support possessing the desired rigidity to properly sustain the applicable load either when fully extended or when within the range of maximum extension; to provide a support of the character stated of round or substantially round cross-section and with its external or exposed surface free of obstructions; to provide, if desired, a watertight support so as to protect the driving or operating mechanism from the action of the elements; to provide simple, inexpensive and compact means for insuring the positive advance and positive return of the telescopic units, the same to include, if desired, devices for reducing friction, such as ball bearings or the like; to provide a telescopic structure, which is automatically locked or gripped in any position to which it may be adjusted; and to provide a structure in which the telescopic units may be ordinary pipe sections so as to reduce the first cost as well as the cost of maintenance.

While the present embodiment was designed especially as an aerial-carrying mast to meet submarine requirements its utility is obviously not so limited.

The invention will first be described in connection with the accompanying drawings and will be finally claimed at the end hereof.

Figure 1 is a view principally in central vertical section of a telescopic mast embodying features of my invention, sufficient of the shell and superstructure of a submersible being shown to indicate how the invention is applied to meet submarine requirements. Fig. 2 is a section on line 2—2 of Fig. 1 to show the spline or feather connections whereby the telescopic units are extended or retracted without rotation of the exposed mast sections. Fig. 3 is a section on line 3—3 of Fig. 1 to show the coupling devices for insuring the positive and prompt return

of the sections. Fig. 4 is a sectional view of the mast in raised or extended position; and Figs. 5 and 6 are elevational views of the mast in respectively raised and lowered position.

a, *b*, and *c* indicate, respectively, the shell plating, superstructure and fairwater of a standard type of submarine. These parts are shown and referred to merely to indicate in a comparative way the location, arrangement and general dimension of the anchor or fixed mast section, which substantially houses the other sections when the mast is collapsed.

While the drawings show four telescopic sections it is evident that the number may vary according to the maximum extension desired, the load to be sustained, and upon other attendant conditions.

The bottom section or standard 1 is rigidly mounted in a step or socket member 2, which may be secured to the shell plating *a*. The socket member 2 has a central bore 3, which constitutes a guide bearing for a driving spindle 4. The latter is equipped with screw threads 5 so that it constitutes when turned in one or the other direction an elevating or lowering jack screw. The driving spindle 4 ranges axially of the mast section 1, is supported by a collar 6 bearing against the step 3, or, if desired, against a thrust bearing 7, and extends the desired distance below the shell plating so as to be driven in any appropriate way by hand or power, for example by the hand crank 8.

The movable telescopic sections are indicated at 9, 10 and 11. As will be presently explained they are secured against rotation.

The mast section 9 is directly driven by the driving spindle 4 and the sections above it are driven indirectly by said spindle through the medium of complementary screw sleeves 12. It will be evident, however, that when the mast is being extended or retracted there is a substantially uniform or progressive feed since the driving spindle and its complementary screw sleeves are united for rotation by suitable spline or feather connections and the internal diameters of the respective screw sleeves are such as to permit each to slide freely over the threaded surface of the next smaller sleeve.

Mast section 9 telescopes the fixed section 1 and is formed or provided near its lower extremity with a tapped member or nut 13,

which engages the threads 5 of the driving spindle so as to be raised and lowered thereby, the nut and of course the section carrying it being held from rotation with the screw by a spline or feather 14 operating in a keyway 15.

The sections 10 and 11 are formed or provided with similar tapped provisions or nuts 16 and 17, which coöperate with the respective screw sleeves 12, it being understood that each pair of mated sections is equipped with appropriate feather connections, as clearly shown at 14, 18, 19 and 20 in Fig. 2, whereby the mast sections proper are advanced or retracted without rotating, but without resisting the rotation of the sleeves 12.

The top mast section is provided with a summits part or cap 21 with ears 22 for attachment of the aerial.

To protect the driving mechanism against the action of the elements and with the view of making the mast, particularly in the retracted position, watertight, I provide a water-shedding arrangement consisting of overhanging rims or flanges 23, which are adapted and arranged to coöperate with packing provisions 24 at the exposed end of each section. So also there may be a stuffing box connection 25 to insure watertightness where the driving spindle penetrates the shell plating.

In order to insure of a quick, uniform and positive retraction of the telescopic units in response to a retrograde movement of the screw, each screw sleeve 12 is provided at its lower end with a collar 26 and with a circular path or recess above the same for the reception of a pin or key 28 secured in the opposite mast section. This pin-and-slot arrangement constitutes a simple form of interlock, which is idle or of no effect during the extension of the mast, but which becomes active under a retrograde feed and insures the return of the parts in a simple yet positive way.

In addition to the thrust bearing 7, the thrust bearings 29 may be provided if necessary or desirable.

It is evident that in a mast constructed according to my invention all stresses are evenly distributed, each section assuming its own share of the load and mutually supporting and aiding the others.

The general construction of the parts and the type of drive also operate as an automatic lock to prevent the accidental quick closing of the sections. Moreover since the mast is substantially of round cross-section it may be inexpensively constructed of pipe sections, which will also materially reduce the cost of maintenance.

Having described the nature and objects of the invention, I claim:—

1. A support adapted for extension and

retraction and capable of sustaining the applicable load at any point within its range of movement, comprising telescopic outer sections, telescopic driving sections, splines connecting both sets of sections in pairs, and an actuator for the driving sections.

2. A support adapted for extension and retraction and capable of sustaining the applicable load at any point within its range of movement, comprising telescopic outer sections, telescopic driving sections, splines connecting mated sections, means for operating the driving sections, and means for insuring the prompt return of the outer sections in response to retraction of the driving sections.

3. A support adapted for extension or retraction, comprising telescopic outer sections, telescopic inner sections, and positive means including spline connections for advancing or retracting both sets of sections without rotating the outer sections.

4. A collapsible mast, comprising telescopic mast sections, telescopic driving sections contained within the mast sections, and a screw coöperating with said driving sections to raise or lower the mast sections.

5. A collapsible mast, comprising telescopic mast sections, telescopic driving sections contained within the mast sections, a screw coöperating with the driving sections to raise and lower the mast sections, and splines to prevent rotation of the latter.

6. A collapsible mast, comprising telescopic mast sections, telescopic driving sections contained within the mast sections, an actuator connected with said driving sections, and means to insure the positive return of the mast sections.

7. A collapsible mast, comprising the combination of a fixed support, a screw mounted for rotation therein, telescopic mast sections mounted relatively to the support so as to be housed thereby when retracted, and complementary telescopic driving sections contained within the mast sections and arranged for coöperation with the screw.

8. In combination with a support, an aerial carrying mast comprising a fixed section having a stuffing box connection with the support, a screw mounted for rotation in said fixed section and extending beyond the stuffing box to a suitable source of power, telescopic mast sections adapted to be raised or lowered with relation to the fixed section, and means within said telescopic sections and coöperating with the screw for advancing and retracting them.

9. A collapsible mast, comprising telescopic mast sections, telescopic driving sections contained within the mast sections, a screw coöperating with said driving sections to raise and lower the mast sections, and anti-friction provisions for taking the thrust of the screw and of said driving sections.

10. A collapsible mast, comprising telescopic mast sections, telescopic driving sections contained within the mast sections, a screw coöperating with said driving sections to raise and lower the mast sections without rotation of the latter, and watershed provisions for the joints.

In testimony whereof I affix my signature in the presence of two witnesses.

ORIN P. LIVELY.
